Attorneys.

United States Patent Office.

ANDY M. ADAMS, OF WASHINGTON, DISTRICT OF COLUMBIA.

Letters Patent No. 101,803, dated April 12, 1870.

IMPROVEMENT IN PADLOCKS.

The Schedule referred to in these Letters Patent and making part of the same.

To all whom it may concern:

Be it known that I, ANDY M. ADAMS, of Washington city, District of Columbia, have invented a new and useful Single-spring, Self-fastening Lock; and I do hereby declare the following to be a full and exact description thereof, reference being had to the accompanying drawing making part of this specification, in which—

Figure 1 represents the back and rim of the lock;

Figure 2, the lower stay of the locking-bolt;

Figure 3, the dog, by means of which the key opens the lock;

Figure 4 represents the lock open, and the top and interior plates removed, so as to show the parts;

Figure 5, the locking-bolt;

Figure 6, the tumbler of the locking-bolt;

Figure 7, the interior plate;

Figure 8, a strong, metal, arc-shaped bolt, extending around nearly the entire interior of the lock, and by means of which the hasp is thrown out of the lock, and the locking-bolt D held back while the hasp is out, and held forward while in; to the back of this bolt is attached the spring H, the office of which will be described fully hereafter;

Figure 9 represents the lock when closed; and

Figure 10 represents the key of the lock.

Similar letters of reference indicate corresponding parts in all the figures.

A is the back of the lock;

a, the rim;

B, the lower stay of the locking-bolt D; and

b b' are its lower guides.

C is the dog, by means of which the stay B is pressed down so as to clear the locking-bolt D, on its being thrown back by the key;

c is the pillar of the lock, and also the pinion of the dog C;

D is the locking-bolt; and

d d', the guides forming its channel.

E is a tumbler pivoted to the locking-bolt.

F is the interior plate, which covers the dog C, forms the upper guide for the lower stay B, and fills the center ward of the key.

G is the arc-shaped bolt, described before as fig. 8.

H is the mainspring, which is attached at one end to the bolt G, and by means of which said bolt is operated and the hasp thrown out of the lock.

h is an extension of the spring H, by means of which the under stay B is driven up when the locking-bolt D is moved forward.

J is the hasp, and

j, its catch.

K is the key.

My invention consists in a single-spring, self-fast-

ening lock, the parts of which are few and simple, yet novel and strong, and so constructed and arranged as to offer perfect security against all attempts to open it otherwise than with a key made as herein shown.

The operation of fastening my lock is as follows:

The hasp J, on being pressed down into the lock, strikes the table-end g of the bolt G, thereby sliding it down on the pivot g¹, compressing the mainspring H and freeing the front end d⁴ of the locking-bolt D, while the end g² of the bolt G forces forward the locking-bolt D in its channel until it enters the catch j in the hasp J. This action permits the rising of the lower stay-bolt B, by means of the spring h, up into the recess d² of the locking-bolt D, thereby bolting it into the catch j in the hasp J. This action also throws the end e of the tumbler E up into the recess e¹ in the upper or straight portion of the rim of the lock, and the recess c² in its other end over the tooth e³ in the side of the table-end g of the bolt G.

By this operation it will be seen that the locking-bolt D is held or locked in the catch j of the hasp J, first, by the under stay B passing up into its recess d²; second, by the end g² of the bolt G pressing against its end; and, third, by the spur e of the tumbler E passing into the recess e¹ in the upper rim of the lock.

It will be noticed that the under side of the bolt G is cut away to admit the spring h passing under it, and that the under side of the under stay B is also cut away, so as to admit of the passage of the same spring under it, and to form a shoulder on it for the said spring to rest against.

The operation of opening the lock is as follows:

The key is pushed down in the lock until its toe is passed in under the interior plate F, when the key is turned to the right, which causes its toe to strike the shoulder e' of the dog C, and turns it down on the shoulder of the under stay B. The upper half of the shoulder of the key strikes the tumbler E, lifting one end of it off the tooth e³ in the table-end g of the bolt G, and the other end down out of the recess e¹ in the rim of the lock, thus freeing the locking-bolt D, which, when freed, is driven back out of the catch j of the hasp J, by means of the lower half of the shoulder of the key pressing against the tail d² of the locking-bolt. The hasp J, being thus freed, is thrown up out of the lock by means of the mainspring H shooting up the table-end g of the bolt G into the recess d² in the front end of the locking-bolt D, which serves to hold back the said bolt. This upward movement of the table-end g of the bolt G carries up with it, by means of the tooth e³, one end of the tumbler E, while the other end is thrown down over the shoul-

der of the guide d' , and thus prevents the locking-bolt D being shot out by any sudden jolt given to the lock, such as a fall, &c.

All of the parts of the lock may be made of cast malleable iron.

The shell of the lock is put together by means of the rivets a^2 .

Having thus fully described the nature and operation of my invention,

What I claim as new, and desire to secure by Letters Patent, is—

1. The bolt G, formed as shown, and provided with slot and pivot g^1 , and pivot e^2 , and spring H, constructed, arranged, and operating in the manner and for the purpose herein set forth and described.

2. The tumbler E, formed as shown, and operating in connection with the bolts D and G and the recess e^1 , in the manner and for the purpose herein described.

3. The locking-bolt D, under stay B, dog C, and guides $b' b'$ and $d' d'$, combined and operating in the manner and for the purpose herein set forth and described.

In testimony that I claim the foregoing lock as my invention, I have hereunto set my hand, this 22d day of January, 1870.

A. M. ADAMS.
